KNOB ACTUATED COMBINATION LOCK

Edward M. Miller, Kent, Ohio, assignor to The C. L. Gouglas Machine Company, Kent, Ohio, a corporation of Ohio

Application September 15, 1953, Serial No. 380,273

2 Claims. (Cl. 70—149)

This invention relates to locks of the combination type, and more particularly to combination locks especially adapted for use on the outside doors of buildings and residences, or on the doors to closets, storerooms, and the like where locking means is necessary or desirable.

An object of my invention is to provide a novel and improved locking means which will retract a conventional spring-projected lock bolt by the rotation of the outside door knob, only after the operation of a combination.

A further object of my invention is to provide a locking means with the above described characteristics having an inside knob, the rotation in either direction of which will retract a spring-projected lock bolt, accomplishing this independently of the combination locking means, and responsive at all times to the hand of the operator.

Still another object of my invention is to provide a locking means as above described which can maintain, in outward appearance, all of the characteristics and advantages of conventional door locks and in addition to this provide the convenience of a single unlocking and bolt retracting means.

Another object of my invention is to provide a lock which, in addition to the above features, will maintain itself in an unlocked condition after the combination has been worked, and will not release the combination unless operated deliberately in the manner necessary to bring this about.

A further object of the invention is to provide a novel arrangement wherein an outside-knob-operated part is normally disconnected from latch-bolt-withdrawing parts but wherein a combination follower, when the combination is properly manipulated, will key or lock these two parts together after which the outside knob will withdraw the latch bolt.

Still other objects and advantages will become apparent from the following description of one embodiment of my invention and a study of the accompanying illustrations in which:

Fig. 1 is an elevational view of that portion of a door which contains its locking means as seen from the bolt projecting edge thereof;

Fig. 2 is an assembly view in section taken along the line 2—2 of Fig. 1;

Figs. 3, 4, 5, 6, 7, 8, 9, and 10 are taken respectively along the lines 3—3, 4—4, 5—5, 6—6, 7—7, 8—8, 9—9 and 10—10 of Fig. 2;

Fig. 11 is an exploded perspective view of the combination lock, housing, and associated parts;

Fig. 12 is a side view of a cam plate and shaft;

Fig. 13 is a side view of a secondary housing;

Fig. 14 is an exploded perspective view of the bolt retracting means most immediately associated with the inside door knob;

Fig. 15 is an exploded perspective view of the bolt retracting means most immediately associated with the

2

bolt, and the combination lock of Fig. 11 fully assembled;

Fig. 16 is a side elevational view of the cam plate of Fig. 12 taken from the left hand side thereof;

Figs. 17 and 18 are plan views, enlarged, of the combination lock of Fig. 11 fully assembled and in each of two operating positions; and

Fig. 19 is a detailed sectional view taken along line 19—19 of Fig. 18.

Referring now to the drawings in all of which like parts are designated by like reference characters, at 10 I show a door in which is mounted, in conventional fashion, a locking means 20, said locking means being positioned in a cylindrical transverse aperture 11 and terminated on either side of the door 10 by door knobs 21 and 22 as best shown in Figs. 1 and 2.

In the bolt projecting edge 12 of the door 10 there is provided another cylindrical aperture 13, the axis of which lies in a horizontal plane with, but perpendicular to, the axis of the transverse aperture 11 and communicates therewith. In the aperture 13 there is positioned a spring-projected lock bolt assembly 14 consisting of a bolt 15 from the rear of which extends a bolt retracting link 16 which is threaded into the bolt. The retracting link 16 as best seen in Fig. 8 terminates at its rearwardly disposed end in a ring 16a and is thereby pivotally secured to a bolt retracting post 17 which, as will later appear, is operable by the door knobs 21 and 22.

The lock bolt 15 is perpetually urged outwardly toward the door edge 12 by a spring 18a which is held captive within a cup shaped container 18 mounted upon the rearwardly disposed side of a conventional face plate 19. An aperture 19a in the face plate 19 allows a reduced portion 15a of the bolt 15 a limited extension outwardly beyond the face plate for engagement with the usual keeper aperture in the door jamb. The bolt retracting link 16 extends rearwardly through an opening 18b in the cup shaped container 18, thereafter terminating in the ring 16a.

The door knobs 21 and 22 are positioned respectively on the inside and outside of the door 10. The inside knob 21 is provided with a reduced portion 23. Said portion 23 is axially bored to receive a hollow cylindrical shaft 31 which extends laterally toward the inside of the door from a circular cam plate 30 and is an integral part thereof. On the opposite side of the cam plate 30 there is provided a cam 32. The cam 32 as shown in Figs. 10 and 14 consists of a substantially thickened fraction of the cam plate 30 circumferentially terminated in sharply perpendicular, radially disposed cam surfaces 33.

The cam 32 is held in position by means of a retaining shell 34, centrally apertured to receive the cylindrical shaft 31 and to allow oscillation therein. By means of a set screw 23a the knob 21, at its reduced portion 23, is rigidly held upon the protruding portion of shaft 31 and rotation therebetween prevented. The shell 34 is firmly attached to the inside of door 10 by screws 34a.

The oscillation of the cam 32 is restricted by virtue of two cam-follower arms 37 which project laterally through elongated slots 41 of a circular slide base 40 directly into the circumferential path of the radially disposed cam surfaces 33. The slide base 40 has an outer diameter of a dimension larger than the transverse aperture 11 in the door 10. A diametrically centered thickened portion 40a of the slide base 40 is projected into the transverse aperture 11. The thickened portion 40a is circular and of a diameter suitable to enable it to fit snugly within the aperture 11 when the remaining outer area of the slide base 40 is against the inside of the door 10. The slide base 40 is held in this position by means of machine screws or

small bolts through apertures 43, thereby cooperating in the assembly of the locking means 20 in a manner herein later to be described.

As shown in Fig. 14, the laterally projecting cam follower arms 37 form extensions of a slide 38. The slide 38 is of such dimension that it fits slidably within a race 44 (Fig. 9) cut horizontally across the center of the thickened portion 49a of the circular slide base 40. The race 44 is cut to such a depth as to allow the slide 38 laterally movable captivity beneath a circular slide cover 45, the diameter of which corresponds to that of the thickened portion 49a of the slide base 40. The lateral movement of the slide 38 is limited to the extent that the cam follower arms 37, projecting at right angles from its surface, can move within the elongated slots 41 cut through the slide base 40. The slide base 40, the slide 38, and the slide cover 45 are assembled by means of screws projected through apertures 45a in the slide cover 45 and into suitable threaded apertures in the portion 40a of the slide base 40.

One end of the slide 38 is provided with a sleeve 39 projecting outwardly from the surface of the slide in a direction opposed to that of the cam follower arms 37. The slide cover 45 is notched at 46 to allow free lateral movement of the sleeve 39 as it is carried with the slide 38. Within the sleeve 39 there is pivotally positioned the bolt retracting post 17. A slot 42 in the slide base 40, positioned between and somewhat to one side of slots 41, allows free movement of that portion of the post 17 which extends beyond the surface of the slide 38. Thus it is assured that any movement on the part of the slide 38 will result in a corresponding movement on the part of the post 17, the bolt retracting link 16, and, consequently, the bolt 15.

In view of the interrelationship of the above described mechanical elements, it follows that rotation of the inside door knob 21, and thereby the cam plate 30 through the shaft 31, will cause a lateral movement of the slide 38 by the action of the cam 32 and either one of its camming surfaces 33 upon one of the cam follower arms 37. The slide 38, through sleeve 39, transfers this motion to the post 17, upon which is pivotally mounted the retracting link 16. By means of lateral movement of the link 16 the bolt 15 is retracted until the reduced portion 15a is flush with the face plate 19 and the door 10 is unlatched. It is also evident that oscillation of the inside door knob 21 in either direction will thus withdraw the latch bolt.

The outside door knob 22 is provided with a reduced portion 24 axially bored to receive a hollow cylindrical shaft 51 which extends laterally toward the outside of the door 10 from the surface of a circular centering member 50 and is an integral part thereof. The centering member 50 has a circumferential flange 52 from the inside surface of which projects a collar 53. The centering member 50 is held in position by means of a retaining shell 54 which is fastened to the outside of the door 10 by screws 54a. By means of a set screw 24a the knob 22, at its reduced portion 24, is rigidly held upon the shaft 51 and rotation therebetween prevented.

The centering member 50 has an axially located internally splined aperture 55 provided for the reception of an externally splined portion 72 of a shaft 71. The shaft 71 extends outwardly from a cam plate 70 located in the interior of the locking means 20, see Figs. 11 and 16.

Referring now to Fig. 11, the mechanism embodying the combination feature of the locking means 20, including the above-mentioned cam plate 70, is contained in a main housing 80 which in the present embodiment is cup-shaped. The housing 80 has a cylindrical wall 82 adapted to fit snugly within the transverse aperture 11 of the door 10. The bottom 81 of the housing 80 has a flange 81a of a larger diameter than the transverse aperture 11, which is positioned against the outside surface of the door 10 when the housing 80 is assembled therewith. In the wall 82 formed two diametrically opposite internally

threaded posts 83, which project outwardly from wall 82 and fit semicircular offsets 11a in the transverse aperture 11 to prevent rotation of the housing 80.

Within the main housing 80 there is rotatably nested a secondary cup shape housing 86 of similar construction. The bottom 87 of housing 86 is provided with a central circular aperture 87a surrounded, on its outwardly disposed side, by a collar 88 (Fig. 13). When the secondary housing 86 is nested within the housing 80 the collar 88 projects outwardly through a circular aperture 81b in the bottom 81 of the housing 80. The generally cylindrical wall 89 of the secondary housing 86 is provided with two internally threaded diametrically opposite posts. The posts 90 are angularly offset from the posts 83 thereby insuring rotatability of the secondary housing 86 in one direction and to the extent necessary to the proper functioning of the lock.

It is within the secondary housing 86 that the cam plate 70 is positioned. The shaft 71 of the cam plate 70 projects through the aperture 87a in the bottom of the secondary housing 86, extending well beyond the collar 88 and, at its splined portion 72, rotatably interlocked with the centering member 50. A retaining washer 57 of sufficient diameter is axially located and maintained upon the end of the shaft 71 by a screw 56.

Rotation of the cam plate 70 in response to rotation of the outside door knob 22 is assured by the centering member 50, internally splined at 55 to receive the externally splined portion 72 of the shaft 71, and its cylindrical shaft 51 to which is secured the reduced portion 24 of the outside door knob 22 by means of set screw 24a.

The outside door knob 22 is limited as to its rotatability by three interreacting washers, 60, 64, and 67. The first of these washers, 60, is centrally apertured at 60a to fit over the outwardly extending collar 88 of the secondary housing 86. An internally projecting tab 61 of the washer 60 is keyed into a slot 88a in the collar 88 and rotation therebetween prevented. From the periphery of the washer 60 there radiate two hooks 62 which diverge outwardly at an angle to the outwardly disposed surface of the washer. The hooks 62 are diametrically opposite each other and circumferentially turned or hooked in the same direction. A stop 63 formed out of the washer 60, is bent at right angles to its outwardly disposed surface. The tab 61 and the stop 63 are diametrically opposite and in a line approximately perpendicular to that between the hooks 62.

The outwardly disposed surface of the bottom 81 of the housing 80 is provided with two diametrically opposed outwardly extending posts 84. The posts 84 are positioned outside the periphery of the washer 60 and at a circumferential distance from the hooks 62. A pair of springs 85 (Fig. 4) each of which is looped at one of its extremities upon one of the hooks 62 and at the other 55 of its extremities upon one of the posts 84, constantly urge the washer 60 to rotate in a counterclockwise direction as viewed in Fig. 4. Since the washer 60 is rotatably locked to the housing 86 through its tab 61 in the slot 88a of the collar 88, said secondary housing is likewise 60 biased in the same direction.

The washer 64 is apertured at 64a and rotatably positioned upon that part of the shaft 71 of the cam plate 70 which projects outwardly beyond the collar 88 of the secondary housing 86. From the periphery of the washer 64 there projects a tab 65 of such radial dimension as to be abutted by stop 63 of the washer 60 and have its rotation limited thereby. Diametrically opposite the tab 65 and outwardly bent at right angles to the outermost surface of the washer 64, is a stop 66.

The washer 67 is centrally and suitably apertured at 67a to fit upon the splined portion 72 of the shaft 71. An outwardly radiating tab 68 so far extends beyond the periphery of the washer 67 as to make circumferential contact with the stop 66 of the washer 67, but not far enough to touch the stop 63 of the washer 60.

The action of the washers 60, 64, and 67 is best understood by reference to Figs. 2, 3, and 4. When the outside door knob 22 is rotated it carries with it in this motion the centering member 50, the shaft 71, and the cam 70 as herein before described. The washer 67, splined upon the shaft 71 at its splined portion 72, responds to this movement. When the tab 68 of the washer 67 strikes the stop 66 of the freely rotatable washer 64, the washer 64 also begins to rotate in the same direction as the washer 67. When the tab 65 of the washer 64 is abutted by the stop 63 of the washer 60, further rotation of the outside door knob 22 in that direction is not possible independently of the secondary housing 86, for said secondary housing 86 is rotatably locked to the washer 60 through its collar 88, slot 88a, and tab 61. The limitation placed upon the outside door knob 22 and its associated parts by the secondary housing 86 will herein later be described, but it is sufficient for the moment that the knob 22 can at all times rotate approximately two turns from either extreme position as determined by the washers 60, 64, and 67.

Accompanying the rotation of the outside door knob 22 and its associated parts as described above is a series of clearly audible "clicks" or "snaps." These sounds are caused by one leg 92a of a flat loop type spring 92 successively snapping into elongated, circumferentially spaced detents 73 on the periphery of the cam plate 70. The spring 92 is shaped at its central portion to be mounted upon a rectangular post 91 located at the periphery of the bottom 87 of the secondary housing 86. As to disposition, the post 91 is circumferentially identical with the wall 89 of the secondary housing 86, said wall having been cut away at 93 to form said post. The other leg 92b of the spring 92 is positioned within the wall 89. The cam plate 70, when in assembled relationship with the secondary housing 86, compresses the legs 92a and 92b of the spring 92. The leg 92a is turned upwardly away from the periphery of the cam plate 70 at 92' thus enabling it to rise out of the detents 73 with equal facility regardless of the direction of rotation of the cam plate.

Upon the inwardly disposed surface of the cam plate 70 there are positioned a plurality of diversely shaped cams 74 of such design and arrangement as to propel a cam follower pin 111 over a predetermined path when the cam plate 70 is oscillated in a predetermined manner. The cam follower pin 111 projects toward the cams 74 from one end of a cam follower arm 110. Projecting in the same direction from the opposite end of the cam follower arm 110 is a pivot pin 109. The pivot pin 109 is pivotally positioned in an aperture 101 located near the edge of a generally circular partition plate 100.

The partition plate 100 has a diameter and peripheral contour which enables it to fit snugly within the confines of the secondary housing 86. Outwardly radiating tabs 102 position the partition plate 100 within the secondary housing 86, the wall 89 of said secondary housing having been cut away at 94, 95, 96 and, as before mentioned, at 93, to accommodate said tabs.

The cam plate 70 is therefore positioned between the bottom 87 of the secondary housing 86 and the partition plate 100. The cam follower arm 110 is pivotally mounted upon the inwardly disposed surface of the partition plate 100 with the cam follower pin 111 extending through said partition plate by virtue of an elongated aperture 103. The elongated aperture 103 describes an arc radiating from the aperture 101. When the cam follower arm 110 is assembled with the partition plate 100, and the pivot pin 109 is inserted in the aperture 101, the cam follower pin 111, responding to the cams 74, arcuately oscillates within the elongated aperture 103.

Upon the inwardly disposed surface of the partition plate 100 there is also positioned an interlocking member 115. The interlocking member 115 is a reversely curved flat strip somewhat S-shaped with the loops being on unequal radii, and with axially directed extensions 118, 75

119 at each end, having a top widely arched at 116 and reversing itself sharply into a lower base portion 117 as best seen in Figs. 17 and 18. When positioned flatly upon the inner surface of the partition plate 100, the interlocking member 115 is slideable in the direction of its greatest dimension within the limits imposed upon it by the wall 89 of the secondary housing 86.

From the base portion 117 of the interlocking member 115 there projects a bolt portion 119 which radiates outwardly through the wall 89 of the secondary housing 86 where it is cut away at 94 and is of sufficient length to extend into the wall 82 of the housing 80, the wall having been cut away at 79 sufficiently to allow this. Therefore, with a bolt 119 in position as shown in Fig. 17 the housing 80 and the secondary housing 86 are rotatably locked to one another. This position is normally maintained by a flat spring 114 fulcrumed around a post 100a secured to and projecting from the inner surface of the partition plate 100 at one of the tabs 102. The shorter leg 114b of the spring 114 is positioned within the wall 89 of the secondary housing 86 while the longer leg 114a presses radially outwardly upon the base portion 117 of the interlocking member 115.

Diametrically opposite the bolt 119 and projecting outwardly through the wall 89 at the cut out portion 96 from the interlocking member 115, is a bolt portion 118. When the interlocking member 115 is in the position shown in Fig. 17, the bolt portion 118 does not extend out of the secondary housing 86 sufficiently to overlap the wall 82 of the housing 80. However, when the interlocking member 115 is in the position shown in Fig. 18 with the bolt 119 having been withdrawn from the cut out portion 79, the top bolt 118 projects into an extensive cut away portion 78 in the wall 82. The portion of the wall 82 of the housing 80 which is cut away at 78 is of such extent as to allow rotation of the secondary housing 86 about $\frac{1}{3}$ of a revolution.

To accomplish withdrawal of the bolt 119 of the interlocking member 115 from the wall 82 at its cut-out portion 79, the cam follower arm 110 is provided with a finger-like extension 112. The extension 112 projects radially outwardly from the pivot pin 109 beyond the cam follower pin 111. The relationship of the partition plate 100, the interlocking member 115, and the cam follower arm 110 is such that the arcuate slot 103 is positioned within the concavity of the arched portion 116 of the interlocking member. When the cam follower arm 110 is oscillated to the farthest outwardly radiating position permitted by the cam follower pin 111 in the arcuate slot 103, the extension 112 touches and exerts pressure against a shoulder 116a of the arched portion 116 of the interlocking member, and cams it outwardly until the bolt 119 is withdrawn from the housing 80 and the bolt 118 is projected into the cut out portion 78 of said housing.

When the cam plate 70 has been oscillated in a predetermined manner by means of the door knob 22, and the cam follower pin 111 has responded to the cams 74 of the cam plate, said pin 111 comes to rest at the position shown in Fig. 17. The cam follower pin 111 is now ready to be cammed outwardly to the periphery of the cam plate 70 by an elongated tapered cam 74a.

The cam 74a touches the periphery of the cam plate 70 at its notched end 75 and angles inwardly from the periphery at its tapered portion 76. Rotation of the cam plate 70 in a counterclockwise direction as seen in Figs. 17 and 18 will force the cam follower pin 111 and cam follower arm 110 in a radially outward direction to the extent permitted by the arcuate slot 103 in the partition plate 100, causing withdrawal of the bolt 119. With the bolt 119 of the interlocking member 115 withdrawn the secondary housing 86 is free to rotate within the housing 80 the distance allowed by the cut-away portion 78 of said housing.

The relationship of the cam follower pin 111, the arcuate slot 103, and the cam 74a (Figs. 18 and 19) is now

such that the cam follower pin is wedged between a notch 75a of the cam 74a and the radially outermost limit of the arcuate slot 103. Upon release of the outer door knob 22 the washer 60, urged by the springs 85 pulling on its hooks 62, returns the secondary housing 86 to its normal position. The retaining ability of the notch 75a into which is keyed the cam follower pin 111 is sufficient to maintain the interlocking member 115 and its bolt 119 in a withdrawn position even upon release of the outer door knob 22 and the return of the secondary housing to its normal position. Thus the housing 80 and the secondary housing 86 remain unlocked in relation to each other until the outer door knob 22, and therefore the cam plate 70, is deliberately rotated in a reverse direction.

To maintain the cam follower arm 110, the interlocking member 115, and the spring 114 in their proper positions against the inner surface of the partition plate 160, there is provided a cover plate 120 as best seen in Fig. 11. The cover plate 120 is generally circular in shape and of a diameter corresponding to that of the secondary housing 86. Apertures 121 are located near the circumference of the cover plate 120 directly in line with the internally threaded posts 90 of the secondary housing 86. By means of screws through said apertures the cover plate 120 is firmly secured at the posts 90 to the secondary housing.

Two diametrically opposite circumferentially disposed lips 122 are provided, said lips being bent at right angles to the cover plate 120 and projecting in the direction of the partition plate. The lips 122 are of such dimension and position as to rest upon those tabs 102 of the partition plate 100 which are positioned in the cut away portions 94 and 96 of the wall 89 of the secondary housing 86.

A third lip 123 projects in the same direction as the lips 122 from one edge of a rectangular aperture 123a in the cover plate 120. Upon that surface of the cover plate 120 disposed toward the partition plate 100 there is provided a leaf spring 124 secured by a rivet 124a at one end, and extending over the edge of the lip 123. Both the lip 123 and the spring 124 are positioned over the cam follower arm 110. Pressure from the spring 124 backed up by the lip 123 is exerted upon the cam follower arm 110 to such an extent that the arm does not oscillate freely, but of such insufficient amount that movement of the cam follower arm by the cams 74 through the cam follower pin 111 is not inhibited.

A second aperture 125 is also provided in the cover plate 120, said aperture 125 being generally rectangular in shape but with a widened portion 126 at one end. The widened portion results in a gently curved edge on one of the longer sides of the rectangular aperture 125, said edge being disposed nearer the center of the cover plate.

In Fig. 15 I show, at the extreme right of an exploded view, the combination mechanism assembly of the locking means 20 as it appears when the housing 80, secondary housing 86, cam 70, partition plate 100, interlocking member 115, cam follower arm 110, and cover plate 120 are in an assembled condition.

Referring still to Fig. 15 and also to Fig. 8, at 130 I show a housing cover which is generally circular in shape and of such a dimension and contour as to match that of the wall 82 of the housing 80. Apertures 131 line up with internally threaded posts 83 in the wall of the housing 80 to facilitate securing thereto. The housing cover 130 has a substantial thickness and a race 132, cut horizontally across its central portion, is provided to allow a slide 138 laterally movable captivity beneath a slide cover 135.

On one end of the slide 138 there is firmly secured the inwardly projecting bolt retracting post 17. The slide 138 is provided, at its upper edge, with an arm 139, outwardly projecting at right angles to the outwardly disposed surface of said slide. A rectangular aperture 133 in the bottom of the race 132 allows free passage of the arm 139, and said arm 139 is long enough to extend into

the aperture 125 of the cover plate 120 of the secondary housing 86. The aperture 133 is of sufficient lateral dimension to allow the arm 139 and therefore the slide 138 horizontal movement. The slide cover 135 is cut away at 136 to the extent that the post 17, mounted upon the slide 138, has adequate lateral freedom.

When the combination mechanism has been properly manipulated and the secondary housing 86 rotatably unlocked from the housing 80, (by withdrawal of bolt 119 from notch 79 of housing 80) continued rotation of the secondary housing 86 propels the slide 138 in a lateral direction by means of its arm 139 in aperture 125 of the rotating cover plate 120. The slide 138 carries with it the bolt retracting post 17 which, through bolt retracting link 16, withdraws the bolt 15 and unlatches the door 10.

Final assembly of the locking means 20 within the cylindrical transverse aperture 11 of the door 10, including the combination mechanism operated by the outside door knob 22 and the bolt retracting mechanism operated by the inside door knob 21, is completed by means of two bolt members 140.

The bolt members 140 include externally threaded portions 141 and internally threaded portions 142 of about equal length. The externally threaded portions 141 project through apertures 137 in the slide cover 135, apertures 131 in the housing cover 130, and are firmly screwed into the posts 83 of the housing 80. The internally threaded portions 142 are adapted to receive bolts or screws projecting through apertures 43 in the slide base 40.

To summarize briefly, the bolt retracting post 17 is laterally movable in a direction away from the bolt projecting edge 12 of the door 10 by either the inside door knob 21 or the outside door knob 22.

The inside door knob 21, through cam 30 and slide 38, withdraws the bolt 15 when rotated in either direction and no other manipulation by the operator is necessary.

The outside door knob 22 withdraws the bolt 15 when said knob is turned from the outside in a clockwise direction as illustrated, but only after the proper oscillation of the combination. This is a known combination lock arrangement whereby alternate clockwise and counter-clockwise oscillation of knob 22 causes follower pin 111 to be cammed radially outwardly until throw-out cam 74a picks up pin 111 in the position of Fig. 17 and carries it to the jammed or final position shown in Figs. 18 and 19. Rotation of the cam plate 70 in relation to the secondary housing 86 and in a bolt retracting direction, ceases when the cam follower pin 111 has been maneuvered into the notch 75a of the cam 74a. However, this action causes the secondary housing 86 to become rotatably disengaged from the housing 80 due to the extension 112 of the cam follower arm 110 exerting pressure upon the interlocking member 115 and thereby withdrawing the bolt 119. The resulting rotation of the secondary housing 86 causes lateral movement on the part of bolt retracting post 17 by means of the slide 138, the arm 139 of which projects into the aperture 125 of the cover plate 120.

As mentioned previously, when pin 111 is in the notch 75a of cam 74, the knob 22 will withdraw the latch bolt 15 until such time as the operator deliberately turns knob 22 in the opposite direction to release pin 111 from notch 75a, thus resetting the combination (pin 111 returns to position near the center of cam plate 70) ready for the next operation.

What I claim is:

1. An outside-knob-operated combination lock comprising a cam plate, a cup shaped housing and a main housing, said cam plate nested within and arcuately oscillatable within but normally rotatably disconnected from said cup shaped housing which is positioned within but normally interlocked with said main housing, a knob operatively associated with said cam plate for oscillating the latter, an interlocking member having a locked position in which it locks said cup shaped housing to said

main housing and having an unlocked position, a cam follower arm, a pin positioned upon the cam follower arm and projecting into said cam plate, a partition plate separating said cam follower arm and said interlocking member from said cam plate and provided with an aperture for the projection of said pin therethrough, a cover plate for said cup shaped housing securely fastened thereto; a slide operatively and slidably associated with said cover plate, a bolt retracting post on said slide, a latch bolt adapted to be oscillatably mounted in a door, bolt retracting linkage connected between said bolt and said post, said cam follower pin, upon proper oscillation by said knob, locking said cup shaped housing to said cam plate at the partition plate, and further rotation of said knob causing withdrawal of said bolt through said cup shaped housing cover plate connection.

2. A knob-operated combination lock comprising a cam plate, a cup-shaped housing and a main housing, said cam plate nested within and arcuately oscillatable within but normally rotatably disconnected from said cup-shaped housing which is positioned within but normally interlocked with said main housing, a knob operatively associated with said cam plate for oscillating the latter, an

interlocking member having a locked position in which it locks said cup-shaped housing to said main housing and having an unlocked position, a cam follower arm, a pin positioned upon the cam follower arm and projecting into said cam plate, a cover plate for said cup-shaped housing securely fastened thereto; a slide operatively and slidably associated with said cover plate, a bolt retracting post on said slide, a latch bolt adapted to be oscillatably mounted in a door, bolt retracting linkage connected between said bolt and said post, said cam follower pin, upon proper oscillation by said knob, locking said cup-shaped housing to said cam plate, and further rotation of said knob causing withdrawal of said bolt through said cup-shaped housing cover plate connection.
